TEMPORARY Porthole Closure

Leonard Kikas, Brooklyn, N. Y.

Application March 11, 1957, Serial No. 645,351

8 Claims. (Cl. 114—174)

This invention relates to closures for the portholes of ships, and more particularly has reference to a closure intended to be applied temporarily to a porthole from the exterior of the enclosure into which the porthole opens.

It is an object of the present invention to provide a porthole closure for ships which can be applied to the porthole from a location disposed exteriorly of the deck house bulkheads or other wall in which the porthole is formed. It is proposed, thus, to permit open portholes to be closed off from outside of a stateroom or other enclosure. In this way, there is eliminated the necessity of entering the stateroom for the purpose of closing the portholes in the event they have been left open, at times when the deck house of the ship is being washed down.

Considerable difficulty has been experienced by washing crews, in washing down the exteriors of a ship's deck house bulkhead, superstructure, or other bulkhead, wall, etc., in which a porthole may be formed.

In such instances, it has been found that portholes may have been left open. Since the swinging closure normally provided upon a porthole can be closed and locked only from the inside of the stateroom, it is necessary for the worker to leave the location at which the washing operations are being performed, find and enter the stateroom, and then close the porthole during the washing operation. Since staterooms are frequently left locked, delays are often encountered, preventing the washing operation from being carried out with the desired speed and efficiency.

In view of the difficulties which have heretofore existed, it is proposed, in carrying out the above stated main object of the invention, to provide a closure device applicable to the porthole from a location exteriorly of the stateroom or other enclosure, and designed to be so applied only temporarily, during the washing operation, with the device sealably engaging the porthole to prevent leakage of the wash water through the porthole into the stateroom, the device being designed for efficient use whether or not the conventional, permanently mounted, porthole closure is in closed or open position.

It is another object of the present invention to provide a closure of the type described which will be characterized by the speed and ease with which it can be applied to the porthole, and will further be characterized by its adaptability for effecting a good sealing action throughout the periphery of the closure.

It is another object of the present invention to produce an effective peripheral sealing action even though the wall of the porthole may be roughened, paint-blistered, or otherwise irregularly surfaced.

It is a further object of the present invention to form the closure in such manner that it can be applied to portholes differing from one another in respect to the diameter thereof, within, of course, a prescribed range of diameters.

Yet another object of the present invention is to form

the device in a manner such that it can be manufactured at low cost, can be used over a long period of time, and will be adapted for trouble-free operation without necessity of frequent replacement or repair of the component parts thereof.

For other objects and a better understanding of the invention, reference may be had to the following detailed description taken in connection with the accompanying drawing in which:

10 Figure 1 is a perspective view showing a fragmentary portion of a hull of a ship, with a closure formed according to the present invention being operatively positioned within a porthole;

15 Fig. 2 is an enlarged sectional view diagrammatically through the closure and porthole, substantially on line 2—2 of Fig. 1;

20 Fig. 3 is a view like Fig. 2, in which the device has been operated to a porthole-sealing, operative position, as distinguished from Fig. 2 in which the closure is in initial position before being caused to sealably engage the wall of the porthole;

25 Fig. 4 is an enlarged elevational view of the device as seen from the outside of the wall or hull, that is, as seen when looking downwardly on Fig. 3;

30 Fig. 5 is an elevational view, on the same scale as Fig. 4, illustrating the inner clamping disc per se, a screw connecting said disc to an outer clamping disc being shown in section; and

35 Fig. 6 is a fragmentary elevational view of the outer clamping disc as seen from the inside of the ship, said outer disc being illustrated per se.

Referring now more in detail to the drawing, a wall, bulkhead, hull, or similar structure of a ship has been generally designated 10, and is formed with a plurality of porthole openings 11 each of which is closed in the conventional manner from the inside by a circular port 12 having the usual hinge brackets 14 receiving hinge pin 16, and having also the conventional handle 18.

As previously noted, difficulty has been experienced in that the porthole can be closed only from inside the stateroom, that is, port 12 cannot be operated to and locked in a closed position from outside the wall, that is, from above the wall viewing the same as in Figs. 2 and 3.

45 The device 20 constituting the present invention is a temporary closure for the porthole, applicable from outside the enclosure into which the porthole opens. The device in actuality comprises certain main components, namely, an outer clamping disc generally designated 21, an inner clamping disc generally designated 22, a threaded connector between the discs generally designated at 24, and an annular, radially extendable sealing gasket 26 engaged between the discs 21, 22.

Outer clamping disc 21 comprises a flat, circular body 27 formed inwardly from its periphery with an annular, continuous, outwardly directed rib 28 the inner surface of which is formed with a correspondingly annular and continuous groove 30 (Fig. 2).

55 Angularly spaced about the periphery of the body 27 are recesses 34, there being four of these angularly spaced 90° apart in a preferred embodiment of the invention, as shown to particular advantage in Fig. 1. Engaged in the recesses 34 are the inner ends of hard rubber tongues 36 extending radially outwardly from the recesses and having outwardly offset free ends as shown in Fig. 2 adapted to bear against the edge portion of porthole 11. The tongues 36 provide stops limiting movement of the device inwardly of the porthole, and fixedly connecting the tongues to the marginal part of the outer disc are screws 38 threadedly engaged in openings formed in body 27 and extending through washers 40 that cooperate with the bottoms of recesses 34 in clampably engaging the tongues 36 in recesses 34.

A center opening is formed in body 27, and a hollow connector screw housing 42, closed at its outer end by a plate 44, is formed intermediate its ends with an outwardly directed flange 46 seating in a shallow, outwardly facing recess of body 27, that communicates with the housing-receiving center opening of the recess. Bolts 48 engage the flange 46 and connect the same fixedly to the body 27.

A connector screw 50, constituting a portion of the connected means generally designated 24, has a coarsely threaded intermediate portion 51, engaging complementary internal threads of housing 42. Screw 50, at its inner end, has an axial recess receiving the stem of a swivel head 52 that seats rotatably in a center recess 53 of the inner disc 22. A cotter pin 54 extends through registering openings of the screw 50 and the stem of the swivel head 52, to connect the same for conjoint rotational movement.

Referring now to the inner disc 22, this includes a flat body 56, integrally formed inwardly from its periphery with a continuous, outwardly directed rib 58 that fits snugly in and slidably contacts the walls of groove 30 of the outer disc.

The marginal portion 60 of disc 22 is slightly thinner than the body 56 as clearly seen from Figs. 2 and 3, and is spaced from the marginal portion of disc 21 to define therebetween a continuous, outwardly opening clamping recess in which is disposed an annular, hollow, resiliently compressible gasket or sealing element 26.

As seen from Fig. 2, the inner face of the disc 21 has, adjacent groove 30, an annular projection 32 having a curvingly depressed surface bearing against the adjacent surface of the gasket 26.

Formed in the body 56, between the center opening and the rib 58, is a large aperture 62, the purpose of which will be made apparent hereinafter.

Means is provided, connected between the discs, to limit the same against relative rotational movement beyond a partial single rotation. Said means includes a hook 64 threadedly connected to disc 22, a chain 68 attached to the hook at one end of the chain (see Fig. 5) and a hook 66 connected to the disc 21. The aperture 62 provides access to the chain, to permit the chain to be disconnected at such time as desired.

In use of the device, the discs are shifted away from each other by rotation of the screw 50 in one direction, so as to dispose the gasket 26 in a relatively wide space between the marginal portions of the discs. The device in this condition of the parts may be readily positioned in a porthole 11, from a location outside the enclosure into which the porthole opens. The tongues 36 limit the device against movement inwardly of the porthole, before the device can engage the port 12.

Thereafter, it is merely necessary that the screw 50 be turned in a direction to shift the discs toward one another. The screw swivels in the body 56, and as a result advances the disc 21 toward the disc 22. This causes the gasket 26 to be placed under compression (Fig. 3) tending to radially expand the gasket out of the marginal groove defined between the respective discs, into sealing engagement with the wall of the porthole as shown in Fig. 3.

When the screw 50 is being turned in a direction to shift the clamping discs toward or away from each other, a handle 29, rigidly secured to and extending outwardly from the rib 28 of the outer disc, can be grasped in one hand to hold the outer disc against rotation during turning of the screw. The chain 68, of course, will then operate to hold the inner disc against rotation relative to the outer disc, except perhaps through a few degrees of a single cycle of rotational movement.

In this way, the porthole is effectively sealed, while the outside of the wall 10 is being washed down, and it is completely unnecessary to enter the stateroom for the purpose of closing and locking the conventional port 12.

When the area surrounding the porthole has been washed, the closure is removed with equal facility, by rotating screw 50 in a direction to shift the discs 21, 22 away from each other, thereby eliminating the grip of the gasket upon the wall of the porthole, to permit the device to be removed and located in the next adjacent porthole. Of course, a substantial number of the devices might be used in a particular operation, so that a corresponding number of portholes can all be closed from the outside, should their ports be in open position. In this way, an area of substantial size can be washed down, after which the several closures 20 can all be removed and placed in the next location to be washed.

While various changes may be made in the detailed construction, it shall be understood that such changes shall be within the spirit and scope of the present invention as defined by the appended claims.

What I claim as new and desire to protect by Letters Patent of the United States is:

- 20 1. A closure for temporarily sealing a porthole, comprising a pair of concentric clamping discs, manually operated means adjustably supporting said discs in predetermined spaced apart parallel relationship for axially shifting the discs toward and away from each other, and 25 a gasket clampably engaged between and extending peripherally of the discs, said gasket being expandable in a direction radially outwardly of the discs responsive to movement of the discs toward each other for sealably engaging the wall of the porthole.
- 30 2. A closure as in claim 1, said gasket comprising a hollow, continuous tube formed of a resilient, yielding material.
- 35 3. A closure as in claim 1, one of said discs having a continuous groove spaced inwardly from the periphery of the disc, the other disc having a continuous rib correspondingly spaced inwardly from its periphery and engaging in the groove for guiding the discs in their movement toward and away from each other, said rib forming a wall bearing against the inner side of said gasket to limit the expansion of said gasket in a direction radially inwardly of the discs.
- 40 4. A closure as in claim 1, one of said discs including a plurality of stops angularly, uniformly spaced circumferentially of said one disc and extending radially outwardly therefrom to engage the edge portion of the porthole, thereby to limit movement of the closure bodily inwardly of the porthole.
- 45 5. A closure as in claim 1, said manually operated means including a screw swivelly connected to one of the discs and having a threaded connection to the other disc.
- 50 6. A closure as in claim 5, further including arresting means detachably connected between the discs limiting relative rotational displacement between said discs.
- 55 7. A closure as in claim 1, said gasket comprising a continuous, annular, resiliently deformable member adapted for compression in a direction axially of the respective discs and further adapted for expansion beyond the peripheries of the discs when so compressed.
- 60 8. A closure as in claim 7, said discs respectively including wall surfaces bearing against the inner side of the gasket in each position to which the discs are shifted toward and away from each other, to limit said gasket against expansion in a direction radially inwardly of the discs.
